PROTECTIVE MEANS FOR RECTIFIER
CATHODESZed J. Atlee, Des Plaines, Ill., assignor to Dunlee
Corporation, Chicago, Ill., a corporation of
Illinois

Application March 4, 1949, Serial No. 79,683

7 Claims. (Cl. 313—240)

1

The present invention relates to electric discharge devices and more particularly to high voltage rectifiers.

In the design of high voltage rectifiers, it is desirable to provide an anode in the form of a cylinder and to arrange a longitudinal filamentary cathode along the axis of the anode cylinder in order to shield the envelope from electron bombardment and minimize accumulation of charges thereby which might adversely affect the operation of the device. Precautionary measures, however, must be taken in order to protect the cathode thus arranged from various destructive phenomena. For example, electrostatic forces resulting from the high potential difference between the anode and the cathode tend to pull the cathode filament laterally from the axial position toward the anode. It will be understood that, if the cathode were mounted in an accurately centered relation upon the axis of the anode, the electrostatic forces would be balanced upon all sides of the cathode and no ill effects would occur. Obviously, such precise mounting of the cathode is impractical, if not impossible, in ordinary factory assembly procedures, with the result that the filament is always more or less eccentric with relation to the anode axis. Any eccentricity of the cathode will result in an unbalance of the electrostatic forces acting upon the cathode and, because of the fact that the cathode when heated to incandescence is inherently relatively weak, these forces may result in the destruction of the filament.

One common method of protecting the cathode from rupture due to electrostatic forces has been to form the lead-in wire supporting the outer end of the cathode into the shape of a spiral consisting of one or more convolutions surrounding the cathode in spaced relation therewith. Since the spiral is of the same potential as the filament, the latter is thereby surrounded with a protective electrostatic field and most of the voltage gradient is taken off of the weak cathode.

One disadvantage resulting from the enclosure of the filament within such a spiral protective shield is that the space charge created thereby seriously impedes electron flow from the cathode to the anode so that a high voltage drop, frequently of the order of 2 to 5 per cent, occurs within the tube. In order to reduce the internal impedance of the tube, the number of convolutions of the spiral are sometimes reduced to a minimum of one or two turns; and, while this had been effective for reducing the internal voltage drop of the tube, the end portions of the fila-

ment are thereby exposed to other destructive phenomena. For example, numerous cathode failures have been observed which are believed to have resulted from inverse bombardment. Inverse 5 ionic bombardment may occur due to the fact that there are always traces of gas present within the envelope and, as a gaseous molecule is struck by an electron, other electrons are driven from such molecule and pass to the anode while the 10 remaining positively charged ion is attracted toward the cathode. Because of the mass of the relatively heavy, positively charged ion and because of the speed imparted thereto by the high potential difference existing between the anode 15 and the cathode, the ion will not, necessarily, be deflected from its path of travel toward the filament by the spiral electrostatic shield and the ion, upon striking the filament, causes a burn-out 20 failure thereof. Such failures of the filament have been observed to occur particularly adjacent the opposite ends thereof where, due to the spiral configuration of the electrostatic shield, the cathode is exposed over a relatively large portion on one side thereof.

Failure of the filament may also occur as a result of the inverse electron bombardment due to 25 electron flow from the anode to the cathode and which may be caused by overheating of some minute projection on the anode surface which, upon reaching incandescence, will, in and of itself, form an electron emitter and from which 30 electrons may flow to the cathode at some relatively unprotected point during the inverse half cycle. The impingement of such inverse electron 35 flow will result in excessive heating of the filament at that particular point giving rise to increased electron emission at that spot which, in turn, will result in increased current flow back to the anode, thus further heating the anode 40 emitter spot causing still further increase in inverse electron flow which condition will progress with extreme rapidity and until terminated by a 45 burn-out of the filament. Whatever the cause for the failures may have been, I have discovered that, with a protective shield formed and arranged in accordance with the present invention, failures of this type have been prevented.

It is a general object of the present invention, therefore, to provide a new and improved shielding arrangement for filamentary cathodes of high voltage rectifier tubes whereby the filament is adequately protected against deleterious effects of electrostatic forces as well as against inverse bombardment while at the same time maintaining interelectrode impedance at a minimum.

2

This object is accomplished by the present invention by providing a metal ring around the cathode extending in a plane substantially at right angles to the axis of the cathode at the midpoint thereof, the ring being electrically connected to one of the cathode lead-in wires and having a diameter at least one-half the length of the cathode filament.

In accordance with the preferred embodiment of the invention, I prefer to utilize a thoriated and carbonized tungsten filament whereby adequate electron emission may be obtained with a cathode filament of relatively short length. In accordance with common practice, the filament is wound in a compact helical form in order further to maintain its overall longitudinal dimensions at a minimum. Upon turning the tube on and off, inductive forces acting upon the filament turns impose a rather severe mechanical force thereupon. Changes in temperature of the filament as the energizing current is turned off and on also impose mechanical strains upon the filament. As is well known in the art, a filament of this nature is relatively brittle and failures may result upon the imposition of these stresses because of the lack of sufficient resiliency in the filament itself. In accordance with the present invention, I overcome failures resulting from these latter causes by providing a resilient, tensioning spring means in the cathode supporting structure for compensation of strains thus imposed upon the cathode helix.

A further object of the present invention, therefore, is to provide a new and improved supporting arrangement for cathodes of electric discharge devices of the type referred to including a resilient element for absorbing excessive tensile strains imposed upon the cathode.

Additional objects and advantages of the present invention will become apparent as the following description proceeds and taken in connection with the accompanying drawing forming a part of the present disclosure.

In the drawing, Fig. 1 is an elevational view of a high voltage rectifier constructed in accordance with one form of the present invention; Fig. 2 is a sectional view taken longitudinally of the anode to show the relative positions of the filament and protective arrangement; and Fig. 3 is a view taken along the line 3-3 of Fig. 2; Fig. 4 is a modification of Fig. 2, showing an alternative arrangement of the tensioning spring.

Referring to Fig. 1 of the drawing, a high voltage rectifier is shown comprising an envelope 10 having a cylindrical anode structure 11 supported in one end and a cathode structure supported in the opposite end thereof. The tube illustrated in this instance is particularly suitable for X-ray use, is highly evacuated, and designed for operation at 110,000 volts. The anode consists of a cylindrical cup arranged coaxially with the envelope 10 and which is supported upon a re-entrant sleeve portion of the envelope and through which lead-in connection is made to the anode.

The cathode structure includes a metal bonnet 19 supported in any suitable manner upon the reentrant portion 17 of the envelope and about which the lower end of the bonnet skirt extends. Extending upwardly from the metal bonnet 19 is a first heavy gauge lead-in wire 20 arranged parallel with the axis of the anode cup 11 and disposed at one side thereof, the upper end of the lead-in wire being doubled back upon itself as indicated at 21. The second lead-in wire 22

extends through the opening 18 in the bonnet 19 substantially along the axis of the cup 11. Secured to the upper end of the lead-in wire 22 is a helical coil element, or spring 23 of relatively heavy gauge resilient metal while the cathode 24 is connected between the adjacent ends of the lead-in wire portion 21 and the resilient spring element 23 and extends substantially along the axis of the anode cup.

It is preferred that the cathode 24 be wound in a compact helix and be formed of carbonized thoriated tungsten, such as described, for example in U. S. Patent No. 2,332,428 to Atlee et al. Such filaments have the advantage of high rate of electron emission at relatively low temperature whereby for any given output the overall dimensions of the filament may be reduced considerably as compared with pure tungsten. Surrounding the cathode 24 is a metal ring 30 and which is supported upon the upper end of a length of wire 31 secured at its lower end to the bonnet 19 through which connection is made to the lead-in wire 20. The ring 30 extends in a plane at right angles to the axis of the anode 11 and substantially at the midpoint of the cathode 24. The diameter of the ring 30 is not less than one-half the length of the cathode 24 while the relative diameters of the ring 30 and the cup 11 are determined by the operating voltage of the device. Generally the diameter of the ring 30 with respect to the inner diameter of the anode cup 11 will be substantially in the ratio of $1/e$, e being the base of natural logarithms.

With the ring 30 surrounding the cathode 24 substantially at the midpoint thereof and connected to the lead-in wire 20, the space charge created thereby is insufficient to interfere substantially with the electron flow between the cathode 24 and the anode 11. It will be observed that the ring 30 extends around the lead-in wire 20, and further, that the ring is substantially concentric with the cathode as well as the anode cup.

In tubes which have been actually manufactured according to the present invention and used, the normal voltage drop has been observed to be less than 1 per cent. Because of the fact that the ring 30 surrounds the cathode 24 at the midpoint thereof, the deleterious effects of the electrostatic field created by the potential differences between the cathode and anode are effectively nullified. While the exposed end portions of the cathode 24 are actually exposed to electrostatic pull, these portions are so short that the electrostatic forces have no appreciable influence thereupon. The practical effect of the ring is to provide a support for the midpoint of the cathode as regards the electrostatic forces acting upon the cathode on opposite sides of the ring.

With the diameter of the ring 30 being relatively large as compared with the overall length of the cathode, substantially complete protection is provided for the cathode against inverse bombardment because of the shorter distance existing between the anode cup 11 and the ring 30, as compared with the distance between the anode and any point of the cathode 24, ions of gas molecules formed within the anode space are attracted to the ring; and, because of its relatively indestructible nature, the impact force of such ions is readily absorbed thereby. Also as regards inverse electron flow, any electrons emitted from the anode, such as from surface electricity, will be attracted by the ring 30 by reason of the fact

that it is closer to the anode than any point of the cathode.

Due to the resiliency of the spring 23 arranged between the upper end of the lead-in wire 22 and the lower end of the cathode, mechanical tensile strains imposed upon the cathode due to voltage surges or otherwise are readily absorbed with complete protection provided for the fragile cathode helix.

Irrespective of theory, it has been definitely established that the cathode protective arrangement of the present invention is far superior to any arrangement which has been devised heretofore. Prior to the innovation of the present invention, cathode failures due to one or more of the reasons mentioned above have been quite common. A large number of rectifier tubes have been built according to the invention as described prior to the filing of the instant application and have been placed in service, and not a single tube has failed due to rupture of the cathode for any of the reasons discussed above.

Instead of incorporating a cathode tensioning spring directly in one of the lead-in wires, as shown in Fig. 2, it may be desirable, under certain circumstances, to provide a tensioning spring in the bonnet 19 as illustrated in Fig. 4. In this instance the lead-in wire 35 is longitudinally movable through a cooperating bore in the top of the bonnet 36 and is connected by a flexible section 37 to the lead-in wire portion 38. A stop collar 39 is secured to the wire 35 while a spring 41 is arranged between the collar 39 and a shoulder formed at the lower end of the cooperating bore. The spring 41 under compression holds the cathode under continuous tension and compensates for excessive strains imposed upon the cathode. It will be obvious that, alternatively, the spring may be arranged about the second lead-in wire 42 in the opening 18 with a suitable insulation bushing providing insulation between the lead-in wire 42 and the bonnet.

Having described the invention in what I consider to be a preferred embodiment thereof, it is desired that it be understood that the specific details shown are merely illustrative and that the invention may be carried out according to various other embodiments, all of which are intended to be included within the scope of the following claims.

I claim:

1. In an electric discharge device including an envelope containing a cylindrical anode and an elongated filamentary cathode positioned along the axis of said anode, means supporting said anode at one end of said envelope, a pair of lead-in wires for the cathode mounted in the opposite end of said envelope, a first of said lead-in wires extending parallel with and spaced from said cathode, the upper end of said first lead-in wire being doubled back upon itself and having the outer end of said cathode connected thereto, the second of said lead-in wires being connected to the opposite end of said cathode, the invention consisting of a metal ring surrounding said cathode substantially at the midpoint thereof and lying in a plane extending at right angles to said axis, said ring being electrically connected to said first lead-in wire and having an outer diameter corresponding to at least one half the length of said cathode.

2. In an electric discharge device including an envelope containing a cylindrical anode and an elongated filamentary cathode positioned along the axis of said anode, means supporting said

anode at one end of said envelope, a pair of lead-in wires for the cathode mounted in the opposite end of said envelope, a first of said lead-in wires extending parallel with and spaced from said cathode, the upper end of said first lead-in wire being doubled back upon itself and having the outer end of said cathode connected thereto, the second of said lead-in wires being connected to the opposite end of said cathode, the invention

10 consisting of a metal ring surrounding said cathode substantially at the midpoint thereof and lying in a plane extending at right angles to said axis, said ring being electrically connected to said first lead-in wire, the diameter of said ring being at least one-half the length of said cathode and the diameter of said ring with respect to the internal diameter of said anode being substantially in the ratio of $1/e$, where e is the base of natural logarithms.

20 3. In an electric discharge device including an envelope containing a cylindrical anode and an elongated filamentary cathode positioned along the axis of said anode, means supporting said anode at one end of said envelope, a pair of lead-

25 in wires for the cathode mounted in the opposite end of said envelope, a first of said lead-in wires extending parallel with and spaced from said cathode, the upper end of said first lead-in wire being doubled back upon itself and having the outer end of said cathode connected thereto, the second of said lead-in wires being connected to the opposite end of said cathode, the invention consisting of means for protecting said cathode from destructive electrostatic forces and inverse bombardment, said means including a metal ring surrounding said cathode substantially at the midpoint thereof and lying in a plane extending at right angles to said axis, said ring also extending around said first lead-in wire and electrically connected thereto, said ring being substantially concentric with said cathode and said anode and having an outer diameter corresponding to at least one half the length of said cathode.

4. In an electric discharge device including an envelope containing a cylindrical anode and an elongated filamentary cathode positioned along the axis of said anode, means supporting said anode at one end of said envelope, a pair of lead-

50 in wires for the cathode mounted in the opposite end of said envelope, an annular metal member surrounding said cathode in spaced relation therewith substantially at the midpoint thereof, means electrically connecting said member to one of said pair of lead-in wires, the outer diameter of said member being at least as great as one-half the length of said cathode and the ratio of the outer diameter of said member with respect to the inner diameter of said anode being substantially in the ratio of $1/e$, where e is the base of natural logarithms, whereby the distance between any point on said anode and any point on said cathode is greater than the distance between said point on said cathode and a point on either said member or on one of said lead-in wires, said member providing complete protection to said filament as regards both destructive electrostatic forces and inverse bombardment.

60 5. In an electric discharge device including an envelope containing a cylindrical anode and an elongated filamentary cathode positioned along the axis of said anode, means supporting said anode at one end of said envelope, a pair of lead-in wires for the cathode mounted in the opposite end of said envelope, the invention consisting of means for protecting said cathode

against destructive electrostatic forces and inverse bombardment, said means consisting of a metal loop extending around said cathode and connected to one of said lead-in wires, the outer diameter of said member being at least as great as one-half the length of said cathode and the ratio of the outer diameter of said member with respect to the inner diameter of said anode being substantially in the ratio of $1/e$, where e is the base of natural logarithms, whereby the distance between any point on said anode and any point on said cathode is greater than the distance between said point on said cathode and a point on either said member or on one of said lead-in wires.

6. In an electric discharge device including an envelope containing a cylindrical anode and an elongated filamentary cathode positioned along the axis of said anode, means supporting said anode at one end of said envelope, a pair of lead-in wires for the cathode mounted in the opposite end of said envelope, a first of said lead-in wires extending parallel with and spaced from said cathode, the upper end of said first lead-in wire being doubled back upon itself and having the outer end of said cathode connected thereto, connection means connecting the second of said lead-in wires to the opposite end of said cathode, the invention consisting of a metal ring surrounding said cathode substantially at the midpoint thereof and lying in a plane extending at right angles to said axis, a wire supporting said ring extending parallel with and electrically connected to said first lead-in wire, said connection means consisting of a member relatively resilient in the direction of said axis, the outer diameter of said member being at least as great as one-half the length of said cathode and the ratio of the outer diameter of said member with respect to the inner diameter of said anode being substantially in the ratio of $1/e$, where e is the base of natural logarithms, whereby the distance between any point on said anode and any point on said cathode is greater than the distance between said point on said cathode and a point on either said member or on one of said lead-in wires.

7. In an electric discharge device including an

envelope containing a cylindrical anode and an elongated filamentary cathode positioned along the axis of said anode, means supporting said anode at one end of said envelope, a pair of lead-in wires for the cathode mounted in the opposite end of said envelope, a first of said lead-in wires extending parallel with and spaced from said cathode, the upper end of said first lead-in wire being doubled back upon itself and having the outer end of said cathode connected thereto, the second of said lead-in wires being connected to the opposite end of said cathode, the invention consisting of means for protecting said cathode from destructive electrostatic forces and inverse bombardment, said means including a metal ring surrounding said cathode substantially at the midpoint thereof and lying in a plane extending at right angles to said axis, a wire supporting said ring and electrically connected to said first lead-in wire, tension spring means operatively associated with one of said lead-in wires for exerting a continuous tension upon said cathode to keep it taut, the outer diameter of said member being at least as great as one-half the length of said cathode and the ratio of the outer diameter of said member with respect to the inner diameter of said anode being substantially in the ratio of $1/e$, where e is the base of natural logarithms, whereby the distance between any point on said anode and any point on said cathode is greater than the distance between said point on said cathode and a point on either said member or on one of said lead-in wires.
